DECORATIVE CHRISTMAS TREE BASE

Charles A. Wharmby, Jr., 1137 Dixie Drive,
San Dimas, Calif. 91773

Filed Feb. 5, 1968, Ser. No. 10,431

Term of patent 14 years

(Cl. D35—3)

FIG. 1.

FIG. 2.

FIG. 3.

FIG. 4.

FIG. 5.

The dominant features reside in the solid line portions.
I claim:

The ornamental design for a decorative Christmas tree base, as shown and described.
